(57) **CLAIM**

The ornamental design for a projectile aperture wicking pattern, as shown and described.

DESCRIPTION

FIG. 1 is an isometric view of a cartridge showing my new design of the wicking pattern in the projectile aperture.

FIG. 2 is an isometric view of a projectile aperture showing my new design of the wicking pattern in the projectile aperture.

FIG. 3 is a top view of a cartridge showing my new design of the wicking pattern in the projectile aperture.

FIG. 4 is a cross sectional view along 4-4 of FIG. 3 showing my new design of the wicking pattern in the projectile aperture; and,

FIG. 5 is a cross sectional view along 5-5 of FIG. 3 showing my new design of the wicking pattern in the projectile aperture.

1 Claim, 5 Drawing Sheets
